(57) **CLAIM**

The ornamental design for a spray gun liquid containment device, as shown and described.

DESCRIPTION

FIG. 1 is a perspective view of a new design for a spray gun liquid containment device that has a window that allows the user to visually ascertain the amount of liquid present in the device.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the spray gun liquid containment device is included for the purpose of illustrating and forms no part of the claimed design.
